ARCHIBALD BARR AND WILLIAM STROUD, OF ANNIESLAND, GLASGOW, SCOTLAND,
ASSIGNORS TO BARR AND STROUD, LIMITED, OF ANNIESLAND, GLASGOW, SCOT-
LAND.

APPARATUS FOR THE CONTROL OF GUNFIRE ON SHIPBOARD.

Application filed September 1, 1922. Serial No. 535,821.

To all whom it may concern:

Be it known that we, ARCHIBALD BARR and WILLIAM STROUD, subjects of the King of Great Britain and Ireland, and both of Caxton Street, Anniesland, Glasgow, Scotland, have invented new and useful Improvements in Apparatus for the Control of Gunfire on Shipboard, of which the following is a specification.

10 This invention relates to means for use in determining the correct setting of a gun mounted upon a platform subject to pitching or rolling or pitching and rolling such as a battleship at sea so that it may be fired at any part of the pitch or roll, and the motion which may be either roll or pitch or a resultant of these and with which the invention principally deals will hereinafter be referred to as "rock."

20 Under conditions when the target is right ahead in the prolongation of the fore and aft line of a ship which is rolling but not pitching and assuming that the target and ship are stationary in position and that the gun is elevated to the angle appropriate for the range, the target should be hit if when the gun is fired the angle of roll is zero but if fired when at any other point of the roll a considerable error mainly in azimuth would arise and the object of this invention is to provide apparatus to which motion in conformity with the rock as the rock occurs is transmitted which acting in conjunction with additional mechanism operates to determine the correction required to be applied to the gun in order that it may be fired at each and every point of the rock.

30 In the following description it will generally be assumed that the deflection due to the relative motion of the ship and the target is zero, except when specially referred to.

40 In the general case the errors to be dealt with are a function of four independent variables, viz (1) α , the angle between the bearing of the target and the fore and aft line, (2) φ , the elevation of the gun corresponding to the known range, (3) the angle of roll, and (4) the angle of pitch.

50 We can, however, at once simplify the problem very materially by considering separately (a) the effect of an angular displacement of the platform upon which the gun is mounted about the line of sight to the target, and (b) the effect of an angular mo-

tion in the vertical plane containing the line 55 of sight. Cause (a) will affect the azimuthal correction and only to a very slight extent the correction for gun elevation φ . Cause (b) will not effect the azimuthal correction.

60 In order to effect the separation referred to, we may place at some convenient station on the battleship, say in the fire control room, two motion following mechanisms one for following the rock, the other for following the angular motion perpendicular to the plane of rock. These mechanisms may be mounted together or separately upon a platform or platforms which are rotated about an axis (or axes) perpendicular to the deck or nearly so, in accordance with the change 65 in bearing (or line of sight) of the target. One of these, the follow the rock mechanism, has its horizontal axis (about which it can turn) parallel to the line of sight, while the second has its corresponding horizontal axis 70 perpendicular to the line of sight. As the bearing of the target alters, its value is to be transmitted to the mechanisms so that their axes are constantly maintained azimuthally 75 parallel and perpendicular respectively to the line of sight. The second mechanism having its axis perpendicular to the line of sight will, however, not be required if the gun sight is directed on the target in elevation, nor will it be required if director 80 firing is employed. We may accordingly use one follow the rock mechanism only in such cases. In fact the second motion following mechanism would only be required for pure 85 indirect fire.

90 The follow the rock mechanism may take the following form:—

95 A Mallock (or other) roll indicator may be used, so mounted that its case supporting its stabilized drum can be rotated by suitable gearing so that a pointer on its dial always records the same reading, viz zero roll; then the motion of the said gearing can be employed to impart to any apparatus a motion proportional to the roll. Instead of rotating the case of the roll indicator, we may rotate a pointer so as to keep it in alignment with a mark on the drum of the roll indicator, for example, by hand control.

100 So far as the correction of bearing is concerned, we now have a comparatively simple problem to solve: This correction, instead of being a function of four

independent variables is now a function of two only, viz (1) the rock φ and (2) the angle of elevation φ of the gun corresponding to the known range, and 5 in accordance with this invention motions according to rock φ and angle of elevation φ of the gun may be communicated at any point of the rock to calculating mechanism which operates to give the correction 10 required. For example, a surface cam of any suitable type may be used having two degrees of freedom, one degree of freedom being for settings corresponding to the value of the rock which may be imparted to the 15 cam by the gearing which has restored the index of the roll indicator to zero—the second degree of freedom for settings corresponding to the range, or the corresponding gun elevation φ . 20 In place of a Mallock roll indicator a long period pendulum or a gyro spinning about a vertical axis may be used, and the apparent motion of the gyro (or other roll indicator) be communicated to the surface cam. 25 When the ship or target, or ship and target are not stationary in position, the correction in bearing obtained after the manner described is to be added on algebraically (say by means of a differential gear) to the 30 bearing which in the absence of rock would be communicated to the guns.

The correction for elevation to be applied to the gun for the effect of rock is of secondary importance. If desired, however, this 35 can also be determined and applied by using the same rock indicator and communicating the measure of the rock to a second surface cam which may be of the same general design as that already described but with the 40 cam constructed to correct for elevation instead of for bearing.

In the earlier parts of this description we have assumed that the deflection for no rock is zero. The follow the rock mechanism 45 should, however, in general not have its axis azimuthally parallel to the line of sight, but should have its axis parallel to the azimuthal direction of the gun itself. Provision may be made for moving the platform (or 50 like parts) of the follow the rock mechanism in accordance with the azimuthal direction of the gun, or we may impart to the platform motion in accordance with the azimuthal motion of the gun sight and apply 55 thereto a correction equal to the deflection of the gun, or again we may impart to the platform a motion equal to the algebraical sum of the bearing and deflection in such a way that the azimuthal position of the axis 60 of the rock mechanism is parallel to the azimuthal position of the gun.

An alternative method is to employ a true roll indicator the axis of which is fixed 65 permanently in the fore and aft line of the ship, a true pitch indicator with axis per-

manently on the beam of the ship, to multiply the angular motion of the roll following mechanism by $\cos(\alpha+\delta)$, where δ is the deflection, to multiply that of the pitch indicator by $\sin(\alpha+\delta)$, then add the two results 70 algebraically and employ the result in place of that furnished by the single rock indicator azimuthally controlled to follow the azimuthal position of the gun.

We may modify details in several respects, 75 e. g. we may dispense with the surface cam (at all events so far as the effects of rock upon the correction for bearing are concerned) and replace the surface cam by a simple multiplying gear, the value of the 80 correction in bearing being approximately the angle of rock multiplied by the tangent of the angle of elevation of the gun for the particular range.

An example of construction for dealing 85 with the correction in bearing will now be described with reference to the accompanying drawings, in which:—

Figure 1 represents a vertical section, Figure 2 a vertical cross section, Figures 3 and 4 represent sectional elevation and plan respectively of one means of indicating the bearing correction, and Figure 5 is an elevation showing partly in section a multiple 90 cam device which may be used as an alternative device to replace the apparatus shown in Figures 3 and 4.

In Figures 1 and 2, 1 is a roll indicator of the Mallock type for indicating the rock 100 supported upon pivots 2 2 and completely immersed in a suitable liquid 3 contained in a case 4 provided with a corrugated side 5 (to allow for the expansion and contraction of the liquid with changes in temperature). The indicator 1 has a very small amount of gravitational stability, the total weight of 1 being adjusted so that its weight 105 is just about equal to that of the liquid displaced so that the friction at the pivots 2 2 is extremely small. A window 6 is provided at the top of the case with a mark (not shown) on the lower side. The case is moved back and forwards about the axis of the pivots 2 2 by hand continuously and slowly in conformity with the rock so that this mark is kept opposite a pointer 7 fixed to 1. This operation is effected by handle 10, coupled to a shaft to which is fixed bevel 11 gearing with bevel 12 fixed on shaft 13 to which is fixed toothed wheel 14 gearing with 15 to which bevels 16 and 32 are fixed. The spindle of jockey wheel 17 is fixed to shaft 18 to which is also fixed bevel 19 gearing with bevel 20 fixed to case 1 which is mounted in bearings 22 22 concentric with the axis of the pivots 2 2, (Figure 2) supported on a platform 24 mounted on ball bearings so that it can be rotated in azimuth.

Thus as the ship rocks the observer looking through window 6 moves the handle 10 130

in such a direction and to the requisite amount to keep the case 4 rotated so that pointer 7 (Figure 2) is kept opposite the mark on the window during the rock.

- 5 Consideration must now be given to the means for rotation of case 4 azimuthally in conformity with the bearing of the gun so that the axis of case 4 may be kept directed on the target (in the case of no 70 deflection) or kept parallel to the azimuthal direction of the gun itself when deflection arises. In the former case the value of α is communicated to a shaft 26, in the latter the value of $\alpha + \delta$. Fixed to shaft 26 are two 75 toothed wheels 27 and 28, the former gearing with toothed wheel 29 and the latter with 30. Wheel 29 (loose on shaft 18) is fixed to bevel 31 meshing with jockey 17. Wheel 30 (loose on shaft 18) is fixed to 80 platform 24 supporting case 4. The gears 27, 29 and 28, 30 are in the ratio of 2 to 1 since the angular motion of the spindle of 85 17 is half that of bevel 31. Thus, if handle 10 is fixed and shaft 26 is rotated, platform 24 is rotated through a certain angle while the spindle of 17 is rotated through an equal angle so that there is no relative motion of 90 the bevels 19 and 20.

Thus shaft 26 furnishes means for rotating case 4 in azimuth, while handle 10 furnishes means for rotating case 4 about the axis of the pivots 22 whatever may be the azimuthal position of 4.

The motion of any of the parts 10, 11, 95 12, 13, 14, 15, 16 and 32 gives a measure of the rock. To transmit this measure to the multiplying apparatus shown in Figures 3 and 4 the arrangement in Figures 1 and 2 consists of the bevel 32 (fixed to 15 and 100 16) gearing with a bevel 33 fixed to a coupling 34 (Figure 2). The complementary part of the coupling 34 is shown at 35 (Figure 4) which is fixed to a quick-pitched screw 36 carrying a nut 37. To prevent the 105 nut from rotating it is provided with a pin 38 engaging in a slot parallel with the screw 36 formed in the framework. Thus as the rock is being followed, nut 37 will be moving backwards and forwards along the axis 110 of screw 36 in conformity with the rock.

The circular measure of the rock has next to be multiplied by the tangent of the angle of elevation corresponding to the range of the target. For this purpose the range may 115 be communicated to a conversion box (not shown, but say after the manner of specification of United States Patent No. 1,339,643, dated 11th May, 1920) whereby range is converted into a magnitude proportional to 120 the tangent of the angle of elevation aforesaid. This value is communicated to a wheel 40 (Figure 4) and thereby to wheels 41 and 42 fixed to screws 43 and 44 respectively. Threaded on these screws are two nuts, one 125 65 on each screw, of which only one (viz 45

upon screw 43) is shown in Figure 3. These two nuts are integral with a carriage 46 in which there is formed a slot perpendicular to the paper, and at right angles to the screws 43, 44, Figure 3. In this slot is a 70 closely fitted rack 48 gearing with a long pinion rod 49. Fixed to the rack 48 is a pin 50, engaging in a slot 51 (Figure 4) of the arm 52 pivoted about the fulcrum 53 53. When carriage 46 is in such a position that pin 50 is co-axial with fulcrum 53, the arrangements must be such that the angle of elevation of the gun is zero.

The rotation of pinion rod 49 becomes a 80 measure of the product of the rock and the tangent elevation of the gun corresponding to the range, for the indication of rod 49 is proportional to the displacement of nut 37 from its zero position (i. e. to the magnitude of the rock) and is also proportional to the perpendicular distance from fulcrum 53 to the path traced by the centre of pin 50 as the rock varies and this distance has been made proportional to the tangent of the angle of elevation corresponding to the range of the target; thus the rotation of pinion rod 49 becomes a measure of the required correction of bearing.

In place of the means for indicating the correction as shown in Figures 3 and 4, we 95 may alternatively adopt means as indicated in Figure 5. Here the value of the rock obtained from shaft 34 (Figure 2) is communicated directly to shaft 60. In this case the gearing between handle 10 and bevel 33 (or rather shaft 60) must be altered in such a way that the total rotation of 60 from maximum rock on one side to maximum rock on the other shall be less than one revolution. Thus as the ship rocks a cam surface 100 61 fixed to shaft 60 oscillates in conformity with the rock. The value of the range is communicated (say according to a uniform scale) to the apparatus by the rotation of screw 62 upon which there is threaded a 105 nut 63 (suitably guided) carrying a groove in which slides a rack 64 with sloping teeth gearing with a long spiral pinion 65 whose rotation furnishes a measure of the requisite correction of bearing. Suitable forces either 110 elastic or gravitational keep the roller at the lower end of 64 in contact with the cam surface 61. In this case as the range alters, i. e. as 63 is moved from left to right, the spiral pinion 65 rotates even although the rack 64 does not slide relatively to the nut 63. Thus the spiral pinion 65 is arranged to do the rough motion required while the corrections only are dealt with by the cam surface 61. It will be recognized that in 115 mechanism of this character relative axial motion may be obtained by moving either the cam surface, the plunger or both, and that instead of applying indications according to rock to 60 it may be imparted to 62 120

125

and indications of range or gun elevation instead of being imparted to 62 may be imparted to 60.

While the apparatus illustrated in Figures 3 and 4 is only applicable for the multiplication of two quantities—in the case referred to (1) rock and (2) tangent of elevation of gun—the apparatus illustrated in Figure 5 is capable of giving the resultant value of any function of the two independent variables (1) rock and (2) range. It is therefore capable of being utilized for indicating not only the correction for bearing but also (if cam surface 61 is suitably formed) the correction for range or the correction for the elevation of the gun.

We claim:—

1. Apparatus comprising means for indicating rock, calculating mechanism, means 20 for transmitting to the calculating mechanism motion in accordance with indications of rock and means for transmitting to the calculating mechanism at any point of the rock motion in accordance with a function 25 of the range or angle of elevation of the gun, for the purposes set forth.

2. Apparatus comprising a roll indicator for indicating rock, calculating mechanism, means for transmitting to the calculating 30 mechanism motion in accordance with indications obtained from the rock indicator and means for transmitting to the calculating mechanism at any point of the rock motion in accordance with a function of the range 35 or angle of elevation of the gun, for the purposes set forth.

3. Apparatus comprising a roll indicator for indicating rock mounted capable of azimuthal rotation, calculating mechanism, 40 means for transmitting to the calculating mechanism motion in accordance with indications obtained from the rock indicator and means for transmitting to the calculating mechanism at any point of the rock motion 45 in accordance with a function of the range or angle of elevation of the gun, for the purposes set forth.

4. Apparatus comprising means for indicating rock, calculating mechanism, toothed 50 gear mechanism for transmitting to the calculating mechanism motion in accordance

with indications of rock and means for transmitting to the calculating mechanism at any point of the rock motion in accordance with a function of the range or angle of elevation of the gun, for the purposes set forth. 65

5. Apparatus comprising means for indicating rock, calculating mechanism, hand control means for transmitting to the calculating mechanism motion in accordance with indications of rock, and means for transmitting to the calculating mechanism at any point of the rock motion in accordance with a function of the range or angle 65 of elevation of the gun, for the purposes set forth.

6. Apparatus comprising means for indicating rock in combination with calculating mechanism consisting of a cam surface, a 70 plunger bearing upon the cam surface and having a rack, means for producing relative axial translation of the plunger and cam surface, and a long pinion in gear with the rack of the plunger, for the purposes 75 set forth.

7. Apparatus comprising means for indicating rock, in combination with calculating mechanism consisting of a cam surface rotatable in accordance with magnitude of rock, a plunger bearing upon the cam surface and having a rack, means for translating the plunger parallel to the axis of the cam surface in accordance with range or angle of elevation of the gun and a long pinion in gear with the rack the amount of rotation of which pinion furnishing a measure of the correction required. 80

8. Apparatus comprising means for indicating rock, in combination with calculating mechanism consisting of a cam surface rotatable in accordance with magnitude of rock, a plunger bearing upon the cam surface and having a rack, means for translating the plunger parallel to the axis of the cam surface in accordance with range or angle of elevation of the gun and a long spiral pinion in gear with the rack the amount of rotation of which pinion furnishing a measure of the correction required. 90
